US0D1111000S

(12) **United States Design Patent** (10) **Patent No.:** **US D1,111,000 S**
(45) **Date of Patent:** **** Feb. 3, 2026**

(54) **MOBILE PHONE CASE**

(71) Applicant: **Hamee Global Inc.**, Seoul (KR)

(72) Inventors: **Bum Joon Lee**, Seoul (KR); **Yeeun Son**, Incheon (KR)

(**) Term: **15 Years**

(21) Appl. No.: **35/523,317**

(22) Filed: **Oct. 16, 2024**

(80) **Hague Agreement Data**

Int. Filing Date: **Oct. 16, 2024**

Int. Reg. No.: **DM/242693**

Int. Reg. Date: **Oct. 16, 2024**

Int. Reg. Pub. Date: **Dec. 20, 2024**
